Diagram illustrating a cross-section of a structure. The top part shows a label 'C⁶' and 'Fig. 4.' above a horizontal line. Below the line, the structure is labeled with 'B⁴', 'B', and 'B⁵'. The structure consists of a central circular area with diagonal hatching, surrounded by a rectangular frame divided into four sections. Each section contains a diamond-shaped pattern with a circle inside. The bottom part of the diagram shows a curved line labeled 'B⁶'.

UNITED STATES PATENT OFFICE.

CHARLES E. MILLER, OF CHICAGO, ILLINOIS.

OPERATING MECHANISM FOR TANK-CAR OUTLET VALVES.

Application filed November 26, 1920. Serial No. 426,367.

To all whom it may concern:

Be it known that I, CHARLES E. MILLER, a citizen of the United States, residing at Chicago, in the county of Cook and State of Illinois, have invented a certain new and useful Improvement in Operating Mechanism for Tank-Car Outlet Valves, of which the following is a specification.

My invention relates to operating mechanism for tank car outlet valves, and has for one object to provide means whereby the outlet valve at the bottom of a tank car may be positively and finally seated by an operator at the top of the car. A further object is to provide means for compensating for variations in pressure temperature and arrangement and position of the parts, whereby the valve will be kept seated under all conditions. Another object is to provide means for positively and permanently seating the valve to prevent leakage. Other objects will appear from time to time in the specification.

It is necessary, in connection with tank cars, to have a discharge or outlet valve, and this valve must be at the bottom of the tank. It takes the form normally of an opening with a seat, flat or beveled as the case may be. The valve itself is merely a poppet valve adapted to be moved toward and from the seat; when raised it must be lifted high enough so as to permit a clear flow outwardly, through the valve opening, of the contents of the tank. Experience has shown that while the valve must be at the bottom of the tank the operating mechanism has to be at the top, preferably in the tank dome. By my arrangement I provide an elongated slender valve rod extending clear up through the depth of the tank. This rod is guided at its upper end and because it has at either end pivot pins perpendicular to each other and to the rod the rod forms what is, in effect, a universal joint, so that it cannot interfere with the proper seating of the valve. Associated with this rod I provide a screw and nut arrangement whereby the rod may be moved vertically to move the valve up and down, but in order to prevent buckling or bending of the rod I provide flexible means between the rod and screw whereby tightening of the screw below a certain point at which the valve is seated tends merely to increase the pressure of the flexible or elastic element, and thus even

though the operator may tighten the screw down farther than is necessary still the spring will take care of any increase in pressure and permit the rod to expand and contract under changes of temperature. I also provide a stop means whereby the operator cannot possibly work the screw down far enough to lock the spring.

My invention is illustrated more or less diagrammatically in the accompanying drawings, wherein—

Figure 1 shows a side elevation in part section of that part of a tank car necessary to illustrate my device;

Figure 2 is a sectional view with parts omitted and parts broken away of my device;

Figure 3 a detailed section on a large scale through the spring element and tightening device.

Figures 4 and 5 are detail views of the valve stem guide.

Like parts are indicated by like characters in the drawings.

A is a tank car frame. I have not shown the trucks because they form no part of my invention. Mounted on this frame is the ordinary tank body A'. At the bottom this body is apertured as at A² and immediately below this aperture is a casting A³ riveted to the body, having a discharge spout A⁴ and a valve seat A⁵. A⁶ is the tank dome projecting upwardly from the top of the tank. A⁷ is a manhole through the tank inside the dome, the diameter of the dome itself being appreciably greater than the diameter of the hole in the shell of the tank. A⁸ is a manhole cover inclosing the opening in the top of the dome through which the operator gains access to the tank and to the valve operating mechanism. A⁹ is a poppet valve adapted, when closed, to rest on the seat A⁵. It has a downwardly projecting pin A¹⁰ traveling in a guideway in the bracket A¹¹, so that when the valve is withdrawn from its seat the pin will still keep it in line with the seat and insure a proper return when the valve is closed. The parts which I have above described are merely the ordinary parts of a tank car, and I have described them merely for the purpose of illustrating the application of my invention.

B is a valve stem. It is pivoted to the valve by means of a pin B¹ at its lower end.

and has at its upper end a pin B^2 , the pins B^1 and B^2 being perpendicular to each other and also to the valve stem itself. At B^3 is shown the inwardly projecting portion of the wall of the tank within the dome. B^4 is a bracket bolted to the wall B^3 forming a chord to the circle of the manhole A^7 . This bracket is cut away in a semicircle as at B^5 to engage and provide a guide for the valve stem B . B^6 is a slotted plate adapted to be bolted to the bracket B^4 after the valve stem is in place; and this bracket and plate together form a guide for the upper end of the valve stem. B^7 is what I have called a compensator or spring box. It is connected to the valve stem B by means of the ears B^8 and the pin B^2 . B^9 is a screw projecting upwardly from the compensator B^7 and rigidly attached thereto. B^{10} is a nut in screw-threaded engagement with the screw and this nut is mounted on a bracket B^{11} projecting upwardly from the wall of the dome. B^{12} is a hand-wheel rigidly fastened to the screw, whereby the operator may manipulate the screw and adjust the valve.

In Figs. 2 and 3 are shown enlarged views of this compensator, which comprises an outer cup or housing C , into which is rigidly fastened by the nut C^4 as shown the lower end of the screw B^9 . This housing C is provided with a plurality of outwardly radially disposed lugs C^2 , and to them is bolted a limiting ring C^3 which extends inwardly a short distance beyond the inner wall of the housing. This housing also has about its periphery a plurality of slots C^4 extending downwardly to the bottom of the housing and terminating at a point below its top. The bottoms of these slots are closed by the plate C^5 . C^6 is a floating cup mounted for reciprocation within the housing, having lugs C^6 projecting outwardly to engage the slots C^4 , and on this cup are mounted the lugs B^8 which pivotally carry the pin B^2 . The downward movement of this cup is, of course, limited by the flange C^3 . C^7 is a coil spring contained within the housing and initially compressed between the bottom of the cup and the top of the housing with a pressure in ordinary cases of from 200 to 400 pounds. C^8 is a stop collar associated with the hand-wheel B^{12} and so arranged that it comes into engagement with the top of the bracket B^{11} , thus stopping further downward movement of the screw before the spring can be sufficiently compressed to bring the edge of the cup against the top of the housing, and thus no matter how tightly the operator tries to jam the screw he cannot take all the slack out of the spring and thus the valve is always seated by the force of the spring.

While it will be evident that I have shown in my drawings an operative device, still many changes might be made, both in size,

shape and arrangement of parts, without departing materially from the spirit of my invention, and I wish, therefore, that my drawings be regarded as in a sense dia-
70 grammatic.

The use and operation of my invention are as follows:

When the tank car is empty the operator who desires to close the valve will open the manhole, reach in under the edge far enough to grasp the hand-wheel; he will rotate this wheel, causing the compensator or spring box to rotate with the screw and the valve stem and valve will rotate at the same time. As the screw works down through the nut the parts will all go down, the valve being guided by the pin until the valve is seated. Further rotation of the screw will tend to increase the pressure on the spring beyond the initial 200 pound tension and cause the housing to come down, compressing the spring, but before the spring is completely compressed and the compensator collapsed to the point at which the cup touches the top of the housing the stop associated with the hand-wheel will come into contact with the bracket and no further rotation of the screw will be possible.

Frequently tank cars change in size and shape as the result of distortion in loading or changes in temperature or abuse, and it may happen that the axis of the valve will be out of line with the screw. The arrangement whereby the valve stem is pivoted at both ends along perpendicular lines provides a universal joint connection, making it certain that, even if this happens, the valve stem will not interfere with the seating of the valve. The valve having been permanently seated by the compression of the spring, any change in the relative length of the valve stem and diameter of the tank would only vary the tension on the spring and there will be no danger of buckling the valve or distorting the tank.

As the valve approaches its seat it is rotated and it rotates or grinds its way down on the seat; thus any obstructions which may find their way between the valve and seat will tend to be ground away as the valve is seated, and this grinding action will continue even after the valve is seated while the spring is being compressed, and thus as the valve is brought down to its final tension on the seat it grinds its way or grinds its seat with a constantly increasing pressure.

When it is desired to open the valve, the reverse of this operation takes place and because the downward movement of the cup in the compensator, with respect to the housing, is limited by the plate the screw provides a positive means for unseating the valve.

I claim:

1. The combination with a valve and valve seat of means for simultaneously rotating and seating the valve, an elastic member interposed between the valve and seating means and adapted to be compressed when the valve is seated, and a universal joint connection between the valve and the elastic member. 70
2. The combination with a valve and valve seat of means for simultaneously rotating and seating the valve, an elastic member interposed between the valve and seating means and adapted to be gradually compressed as the valve is rotated after it reaches its seat, and a universal joint connection between the valve and the elastic member. 75
3. The combination with a valve and valve seat of means for simultaneously rotating and seating the valve, an elastic member interposed between the valve and seating means and adapted to be compressed when the valve is seated, and a universal joint connection between the valve and the elastic member, said connection comprising a relatively long and flexible valve stem pivoted at its ends respectively on the valve and the spring member, the pivot lines being perpendicular to one another and to the valve stem. 80
4. The combination with a valve and valve seat of means for simultaneously rotating and seating the valve, an elastic member interposed between the valve and seating means and adapted to be gradually compressed as the valve is rotated after it reaches its seat, and a universal joint connection between the valve and the elastic member, said connection comprising a relatively long and flexible valve stem pivoted at its ends respectively on the valve and the spring member, the pivot lines being perpendicular to one another and to the valve stem. 85
5. The combination with a valve and valve seat of means for simultaneously rotating and seating the valve, an elastic member interposed between the valve and seating means and adapted to be compressed when the valve is seated, and a universal joint connection between the valve and the elastic member, a guide for the valve itself on the side thereof opposed to the seating member and a guide for the valve stem adjacent the elastic member. 90
6. The combination with a valve and valve seat of means for simultaneously rotating and seating the valve, an elastic member interposed between the valve and seating means and adapted to be gradually compressed as the valve is rotated after it reaches its seat, and a universal joint connection between the valve and the elastic member, a guide for the valve itself on the side thereof opposed to the seating member and a guide for the valve stem adjacent the elastic member. 95
7. The combination with a valve and valve seat of means for simultaneously rotating and seating the valve, an elastic member interposed between the valve and seating means and adapted to be compressed when the valve is seated, and a universal joint connection between the valve and the elastic member, said connection comprising a relatively long and flexible valve stem pivoted at its ends respectively on the valve and the spring member, the pivot lines being perpendicular to one another and to the valve stem. 100
8. The combination with a valve and valve seat of means for simultaneously rotating and seating the valve, an elastic member interposed between the valve and seating means and adapted to be gradually compressed as the valve is rotated after it reaches its seat, and a universal joint connection between the valve and the elastic member, said connection comprising a relatively long and flexible valve stem pivoted at its ends respectively on the valve and the spring member, the pivot lines being perpendicular to one another and to the valve stem. 105
9. In a tank car a valve at the bottom of the tank, a valve seating member at the top of the tank, a long flexible valve stem between the valve and the seating member and an elastic means interposed between the stem and the seating member and arranged to permit expansion and contraction of the valve stem. 110
10. In a tank car a valve at the bottom of the tank, a valve seating member at the top of the tank, a long flexible valve stem between the valve and the seating member and an elastic means interposed between the stem and the seating member and arranged to permit expansion and contraction of the valve stem, a seating member comprising a screw and nut, a stop for the screw which comes into action before the spring member is completely collapsed. 115
11. In a tank car a valve at the bottom of the tank, a valve seating member at the top of the tank, a long flexible valve stem between the valve and the seating member and an elastic means interposed between the stem and the seating member and arranged to permit expansion and contraction of the valve stem, the valve being arranged to rotate both before and after it has been seated by the seating member. 120
12. In a tank car a valve at the bottom of the tank, a valve seating member at the top of the tank, a long flexible valve stem between the valve and the seating member and an elastic means interposed between the stem and the seating member and arranged to permit expansion and contraction of the valve stem. 125

valve stem, a seating member comprising a screw and nut, a stop for the screw which comes into action before the spring member is completely collapsed, the valve being arranged to rotate both before and after it has been seated by the seating member.

13. In a tank car a valve at the bottom of the tank, a valve seating member at the top of the tank, a long flexible valve stem between the valve and the seating member and an elastic means interposed between the stem and the seating member and arranged to permit expansion and contraction of the valve stem, the valve seating member being adapted after the valve has seated, to rotate the valve and simultaneously increase the compression of the spring seating the valve.

14. In a tank car a valve at the bottom of the tank, a valve seating member at the top of the tank, a long flexible valve stem between the valve and the seating member and an elastic means interposed between the stem and the seating member and arranged to permit expansion and contraction of the valve stem, a seating member comprising a screw and nut, a stop for the screw which comes into action before the spring member is completely collapsed, the valve seating member being adapted after the valve has seated, to rotate the valve and simultaneously increase the compression of the spring seating the valve.

15. In a tank car a valve at the bottom of the tank, a valve seating member at the top of the tank, a long flexible valve stem between the valve and the seating member and an elastic means interposed between the stem and the seating member and arranged to permit expansion and contraction of the valve stem, the valve being arranged to rotate both before and after it has been seated by the seating member, the valve seating member being adapted after the valve has seated to rotate the valve and simultaneously increase the compression of the spring seating the valve.

16. In a tank car a valve at the bottom of the tank, a valve seating member at the top of the tank, a long flexible valve stem between the valve and the seating member and an elastic means interposed between the stem and the seating member and arranged to permit expansion and contraction of the valve stem, a seating member comprising a

screw and nut, a stop for the screw which comes into action before the spring member is completely collapsed, the valve being arranged to rotate both before and after it has been seated by the seating member, the valve seating member being adapted after the valve has seated, to rotate the valve and simultaneously increase the compression of the spring seating the valve.

17. In a tank car a valve at the bottom of the tank, a screw and nut at the top, a long flexible valve stem between them, means for rotating the downward movement of the screw and a spring member interposed between the screw and stem, the parts being arranged so that the downward movement of the screw is stopped before the spring is completely compressed.

18. The combination with a valve of a screw adapted to seat it, a valve stem associated with the valve, a compensating device interposed between the stem and the screw comprising a housing, a cup slidable therein but held against rotation with respect thereto, a spring within the housing interposed between the cup and the housing, the valve stem being mounted in the cup.

19. The combination with a valve of a screw adapted to seat it, a valve stem associated with the valve, a compensating device interposed between the stem and the screw comprising a housing, a cup slidable therein but held against rotation with respect thereto, a spring within the housing interposed between the cup and the housing, the valve stem being mounted in the cup, means for limiting the downward movement of the cup in response to the pressure of the spring.

20. The combination with a valve of a screw adapted to seat it, a valve stem associated with the valve, a compensating device interposed between the stem and the screw comprising a housing, a cup slidable therein but held against rotation with respect thereto, a spring within the housing interposed between the cup and the housing, the valve stem being mounted in the cup, a universal joint connection including the valve stem between the cup and the valve.

Signed at Chicago, county of Cook and State of Illinois, this 22 day of November, 1920.

CHARLES E. MILLER.
